AXEL MALM, OF DAYTON, OHIO, ASSIGNOR TO THE EGRY REGISTER COMPANY, OF DAYTON, OHIO, A CORPORATION OF OHIO.

MANIFOLDING DEVICE.

1,110,328.

Specification of Letters Patent. Patented Sept. 15, 1914.

Application filed March 8, 1913. Serial No. 752,864.

To all whom it may concern:

Be it known that I, AXEL MALM, a citizen of the United States, residing at Dayton, in the county of Montgomery and State of 5 Ohio, have invented certain new and useful Improvements in Manifolding Devices, of which the following is a specification, reference being had therein to the accompanying drawing.

10 This invention relates to new and useful improvements in manifolding devices, and the principal object of the invention is to provide a feeding device for webs of paper which will successfully feed lengths of webs 15 to a position where they may be readily severed, without the employment of a carriage for said webs as is common in similar devices now in general use.

Another important object of the invention 20 is to provide an operating means for the feeding device and to provide means for controlling the operating means whereby the feeding device will be regulated so as to successively project uniform lengths of said 25 webs beyond the feeding device.

A further object of the invention is to provide a feeding device including a pair 30 of feed rollers for the webs, and to provide means for intermittently rotating the rollers 35 a predetermined number of times.

A still further object of the invention is to provide a novel means for shifting and 40 positively locking one of the feed rollers in spaced relation to the other roller to permit 35 the webs being readily passed there-between.

In the accompanying drawings Figure 1 45 is a partial top plan view of a register showing the application of one embodiment of my invention, Fig. 2 is a detail longitudinal 50 sectional view there-through, Fig. 3 is a detail view showing the ratchet connection between one of the feed rollers and the operating means, Fig. 4 is a detail sectional view showing the locking pawl for the feed 55 roller, and Fig. 5 is a detail sectional view showing the means for shifting and locking one of the feed rollers in spaced relation to the other roller.

In these drawings I have illustrated one 60 embodiment of my invention and have shown same as comprising a casing A of ordinary construction including side walls 5-5. Centrally supported by these walls is a table 6 which in this instance is detachably supported to permit of ready access to

the interior of the casing. The webs of paper are drawn off paper rolls which are journaled within the casing, and these webs are carried over the table 6 in a manner similar to other machines of this type now 60 in general use. These webs are printed with bills, the lengths of these bills varying to suit the work of different offices. I have, therefore, provided a feeding means for these webs by means of which webs of pre-determined lengths may be successively and intermittently projected to a position where they may be severed. It will, of course, be understood that as many webs may be employed as desired, and that these webs are 65 disposed one upon the other, and carbon sheets disposed intermediate adjacent webs. To this end I have provided a pair of feed rollers 7 and 8. These rollers are disposed transversely of the casing and adjacent the 70 end of the table opposite the end over which the paper webs are fed. The lower roller, or feed roller 7, is loosely mounted upon a power shaft 9 which is journaled in suitable bearings formed in the walls 5 of the casing. 75 Fixed on one end of the roller 7 is a ratchet wheel 10, and fixed on the shaft 9 between the ratchet wheel and the adjacent wall 5 is a gear wheel 11 which carries spring-pressed pawls 12-12 for engagement with 80 the teeth of the ratchet wheel 10. It will thus be observed that upon rotation of the shaft 9 in one direction the gear wheel 11 will rotate therewith, and through the medium of the pawls 12 and ratchet wheel 10, 85

the roller 7 will be rotated in the same direction, but upon the reverse rotation of the shaft 9 the pawls 12 will slide over the ratchet wheel 10 and thereby prevent the roller 7 from being reversed. In order to 90 effectively lock the roller 7 against this reverse movement, and yet permit of the roller having a forward movement, I have provided a pivoted spring actuated locking 95 detent 13, said detent being mounted upon the other wall 5 of the casing and co-operating with a gear wheel 14 that is fixed on that end of the roller 7.

The upper roller 8 constitutes a pressure roller and is provided with trunnions 15 100 which operate in vertical slots 16 formed in brackets 17 carried by the side walls 5. Formed in each bracket 17 directly above the slot 16 is an opening 18 which is closed at its upper end by a threaded plug 19. 110

Disposed within this opening and bearing upon the reduced end 15 of said roller is a bearing shoe 20, and this shoe is pressed downwardly by means of a coil-spring 21 which is disposed within the opening 18 between the plug 19 and shoe 20. The springs serve to press the roller 8 downwardly for frictional engagement with the roller 7 to permit the webs of paper being fed there-through upon rotation of the roller 7 in the proper direction. This movement is imparted to the feeding means by a hand-crank 22 which is fixed on one end of the shaft 9.

In order to facilitate the initial insertion of the paper webs between the feed rollers, the rollers are moved apart, and in order to so space these rollers I have provided a means for shifting the pressure roller 8 away from the feed roller 7 and to lock said pressure roller in its spaced relation. To this end I have journaled a cam shaft 23 in the walls 5 of the casing below the feed roller 7, and fixed to this shaft adjacent each end thereof is a cam finger 24. Each finger 24 operates in a recess formed in the respective side wall 5, one of said fingers being disposed between the gear wheel 11 and the adjacent wall 5, and the other finger being disposed between the gear wheel 14 and the other wall 5. Each finger is centrally formed with an arcuate slot 25 through which the shaft 9 extends, this slot permitting the fingers to have a limited oscillatory movement. The upper edge of each finger is formed with a cam face 26 and a seat 27, the cam face 26 being disposed directly below and in operative relation to the trunnions 15 of the pressure roller 8. When the cam fingers 24 are shifted to the right the pressure roller 8 will be raised against the tensions of the springs 21, and upon the complete movement of the cam fingers 24 the trunnions 15 will be disposed upon the seats 27. In order to rock the shaft 23 and thereby actuate the cam fingers 24, said shaft 23 is provided with a finger lever 28, and in order to assist the fingers in returning to their normal or inoperative positions I have provided a spring 29 which is coiled about the shaft 23 and has one end fixed thereto, the other end being fixed to the adjacent side wall of the casing.

As before stated it is desired to control the feeding means so that uniform lengths of the paper webs may be successively projected beyond the feeding means, and in order to accomplish this function I have provided a rack-bar 30 which is slidably mounted upon the side wall 5 adjacent the gear wheel 11. This rack-bar is formed with an elongated longitudinal slot 31 through which supporting pins 32 pass and are secured to the casing. Rotatably supported by the adjacent side wall is a com-

pound gear, the pinion 33 thereof meshing with the teeth of the rack-bar 30 and the gear 34 thereof meshing with the intermediate gear 35, the latter in turn meshing with the gear wheel 11. It will thus be observed that upon rotation of the shaft 9 in one direction the rack-bar 30 will be shifted, and that the continuous movement of the shaft 9 will be limited by the amount of the sliding movement of said rack-bar. The sliding movement of the rack-bar 30 is regulated in accordance with the lengths of the paper webs to be projected beyond the feeding means, and to adjust the movement of the rack-bar to suit various lengths of webs, I have provided a stop-pin 36 which is adapted to project through any one of a number of openings 37 formed within the side wall. These openings are disposed in alignment with the rack-bar 30 so that said bar will engage the pin in any one of its positions and thereby limit the rotation of the feed roller 7 in one direction.

When these machines are adjusted at the factory preferably only one opening 37 for the stop-pin 36 is formed in the casing, the position of this opening being determined by the length of the bill used by the purchaser of the device. It will, of course, be understood that more than one opening 37 may be formed at the time the device is built so as to accommodate the same to bills of different lengths.

In operation after the several webs of paper have been clamped between the rollers 7 and 8, the crank handle 22 is rotated in a forward direction. The rotation of this handle causes the rack-bar 30 to move toward the stop-pin 36. Therefore, as soon as the bar engages said stop-pin the movement of the crank-handle 22 will be arrested. By this time the proper length of paper webs have been projected beyond the feeding means and are in a position to be readily severed. The handle-crank 22 is then rotated in a clock-wise direction or in a direction toward the table 6. As the shaft 9 is thus rotated the pawls 12 will ride over the teeth of the ratchet wheel 10 as above noted, and the feed roller 7 will be held against rotary movement by the locking detent 13. The crank handle is rotated in this direction until the rear end of the slot 31 engages the pin 32 which checks the return movement of the rack. The crank handle 22 is again rotated in a forward direction and as a result the next length of web is projected beyond the feeding means. By this construction uniform lengths of webs may be intermittently and successively projected, and by adjusting the stop-pin 36 the machines may be employed for bills of different lengths as will be readily understood.

While I have shown and described one embodiment of my invention it will be

understood that this has been chosen for the purposes of illustration only and that I do not desire to be limited to the details of construction shown and described, for obvious modifications will occur to a person skilled in the art.

Having thus described my invention, what I claim as new and desire to secure by Letters Patent, is:—

10. 1. In a manifolding device, the combination, with feed rollers, and means to positively actuate one of said rollers, of coöperating devices to limit the movement of said positively actuated roller, one of said devices being supported independently of and operatively connected with said actuating means and having movement sufficient to permit said roller to make more than one revolution.
15. 2. In a manifolding device, the combination, with feed rollers, and means to positively actuate one of said rollers, of coöperating stop devices to control the movement of said feed rollers, and a geared connection between one of said stop devices and said positively actuated roller, whereby said roller may make more than one revolution for each movement of said stop device.
20. 3. In a manifolding device, the combination, with feed rollers, and means to positively actuate one of said rollers, of coöperating stop devices to control the movement of said feed rollers, and a geared connection between one of said stop devices and said positively actuated roller, whereby said roller may make more than one revolution for each movement of said stop device, and means to regulate the movement of said stop device.
25. 4. In a manifolding device, the combination, with paper feeding means comprising a feed roller, and means for rotating

said roller, of a bar mounted for limited sliding movement, a stop to limit the movement of said bar, and a connection between 45 said bar and said roller to cause the movement of said roller to be controlled by the movement of said bar.

5. In a manifolding device, the combination, with feed rollers, and means to positively actuate one of said rollers, of a geared rack mounted for sliding movements, a geared connection between said rack and said positively actuated roller, and a stop to limit the movement of said rack in one direction. 55

6. In a manifolding device, the combination, with feed rollers, and means to positively actuate one of said rollers, of a geared rack mounted for sliding movements, a 60 geared connection between said rack and said positively actuated roller, and an adjustable stop to limit the movement of said rack in one direction.

7. In a manifolding device, the combination, with a casing comprising side walls, feed rollers mounted on said side walls, and means to positively actuate one of said rollers, of a rack slidably mounted on one of said side walls and a stop arranged in 65 the path of said rack to limit its movement in one direction, a pinion meshing with said rack, and a gear connected with said positively actuated feed roller and with said pinion, whereby the rotation of said feed 70 roller is controlled by the movement of said rack.

In testimony whereof, I affix my signature in presence of two witnesses.

AXEL MALM.
